UNITED STATES PATENT OFFICE.

RICHARD H. HAM, OF STOCKPORT, NEW YORK.

TROLLEY-RETRACTOR.

SPECIFICATION forming part of Letters Patent No. 738,676, dated September 8, 1903.

Application filed January 16, 1903. Serial No. 139,290. (No model.)

To all whom it may concern:

Be it known that I, RICHARD H. HAM, of Stockport, in the county of Columbia and State of New York, have invented certain new and useful Improvements in Trolley-Retractors; and I do hereby declare the following to be a full, clear, and exact description of the invention, such as will enable others skilled in the art to which it appertains to make and use the same.

The primary object of this invention is to provide a trolley-retractor for carrying a trolley-catcher, so that the weight of the latter may be utilized to aid in retracting the trolley.

Trolley-catchers are, as is well known, designed to check the upward flight of a trolley when the wheel jumps the conductor-wire. By my invention as soon as this occurs the retractor is freed and so acts upon the catcher and trolley that the wheel is immediately brought back beneath the wire.

The invention will be hereinafter fully set forth, and particularly pointed out in the claims.

In the accompanying drawings, Figure 1 is a longitudinal sectional view. Fig. 2 is a plan view with parts broken away. Fig. 3 is an end view. Fig. 4 shows a portion of the face-plate and retractor-arm removed.

Referring to the drawings, 1 designates a boxing or casing open at its front and ends and designed to be secured in an upright position to the dashboard of a trolley-car. Extending transversely of the lower end of the casing and mounted in the sides thereof is a shaft 2, designed to form a bearing for the hub 3 of a retractor-arm 4. The hub is shown in the form of a U-shape plate having coincident openings 5 in its laterals 6 to accommodate the shaft, the retractor-arm being integral with or secured to the central body portion 7. Around shaft 2 are coiled the ends of a spring 8, which are secured to ratchet-wheels 9, loosely mounted on the shaft. The central portion of the spring bears against the inner side of the retractor-arm. This central portion may be divided, as when two springs instead of one are employed. Pawls 10 engage the ratchet-wheels to prevent their turning backward under the tension of spring 8. Thus the spring constantly tends to swing the retractor-arm outwardly from the casing.

The ratchet-wheels may be turned to increase the spring tension.

The retractor-arm is in the form of an approximately rectangular frame 12, which is designed to be freely moved into and out of the casing. The outer face-plate 13 is of increased thickness to form a tenon-block 14 of the width of, but less in length than, the opening in the retractor-arm, a bow-spring 15 between the end of the block and the outer end of the arm serving to normally hold the block against the lower end of the frame. The outer edges of the face-plate are designed to be normally seated against the sides of the casing.

16 designates the locking-plate mounted on the inner side of frame 12 and movable longitudinally thereof, together with the face-plate, to which it is secured by screws 17. At its upper or outer end the plate 16 is provided with a hook 18, shown in the form of a lateral shoulder channeled or grooved on its under face. This hook is curved or rounded, so that when forced against a locking-bar 19 it will ride upwardly thereon, and upon passing to the inner side thereof the plates 13 and 16 will be free to move downwardly under the recoil of spring 15, and thus be locked within the casing.

20 designates the trolley-catcher of the form in common use. It is designed to be secured to the face-plate, on the outside thereof, and to have secured thereto the rope 21, fast at its other end to the trolley.

22 designates the buffer designed to contact with a spring 23 to prevent damage to the device or the car in the event of the former being released when the rope is not secured to the trolley.

In practice with the car running under normal conditions the retractor is held within the casing by bar 19 against the tension of spring 8, the two plates 13 and 16 being held at the lower end of frame 12 under the tension of spring 15, although obviously the weight of these parts, coupled with the weight of the catcher, would tend to hold them in such position independently of the spring. Upon the trolley-wheel leaving the conductor-wire the trolley will jump upward, and the rope being arrested by the catcher the upward pull on the latter causes the sliding plates 13 and 16 to move upwardly, thereby

disengaging hook 18 from bar 19 and allowing the retractor-arm under the recoil of spring 8 and the weight of the catcher to instantly swing outwardly, drawing the trolley beneath the wire and precluding the possibility of its coming in contact with the arms by which the latter is supported. As soon as the trolley-wheel is replaced in engagement with the conductor-wire an inward swing of 10 the retractor-arm will cause hook 18 to re-engage bar 19, and thus hold the arm locked, as before, with the trolley-catcher in proper position.

The advantages of my invention are apparent.

The device is simple in construction and operation and free of complicated mechanism.

It is obvious that various forms of trolley-catchers as generally used may readily be secured to a retractor constructed in accordance with my invention, so that the pull on the catcher may be utilized to free the retractor and its weight aid in lowering the latter to draw the trolley below the conductor-wire.

I claim as my invention—

1. In combination, a trolley-catcher and a swinging trolley-retractor, the former being mounted on the latter, and means for normally holding the retractor locked, such means being actuated to release the retractor under a pull exerted on the catcher, the weight of the catcher serving to swing the retractor when the latter is released, as set forth.

2. In combination, a trolley-catcher and a trolley-retractor, the latter comprising a movable member to which the trolley-catcher is secured, and means for normally holding such member locked, such means being actuated to release said member and permit the same to move downwardly together with the catcher under a pull exerted on the latter, the weight of the catcher serving to move the retractor member when released from the holding means, as set forth.

3. In combination, a trolley-catcher and a trolley-retractor, the latter comprising a swinging arm, means for normally holding such arm locked, and a spring acting on such arm, said trolley-catcher being mounted on said arm, said locking means being disengaged upon a pull being exerted on the catcher, and said arm being thereby swung outwardly under the recoil of said spring and the weight of the catcher, substantially as set forth.

4. In a trolley-retracting device, in combination, a pivoted retractor-arm, means tending to swing said arm in one direction, a locking-plate in sliding engagement with said arm designed to normally hold the latter as against

the tension of said swinging means, and a trolley-catcher mounted on the retractor-arm, substantially as set forth.

5. In a trolley-retracting device, in combination, a pivoted retractor-arm, and means tending to swing said arm in one direction, a locking-plate in sliding engagement with said arm to normally hold the latter as against the tension of said swinging means, a face-plate 7c secured to and movable with said locking-plate, and connections between said face-plate and the trolley, substantially as set forth.

6. In a trolley-retracting device, in combination, a pivoted retractor-arm having an open frame, a spring tending to swing said arm in one direction, a face-plate movable in said frame, a locking-plate secured to and movable with said face-plate and tending to normally hold said arm as against the tension of said spring, and connections between said face-plate and the trolley, as set forth.

7. In a trolley-retracting device, the combination with a casing having an open front and ends, and a shaft and locking-bar mounted, respectively, in the lower and upper ends of said casing, of a retractor-arm mounted on said shaft, a spring tending to swing said arm outwardly from said casing, a sliding locking 9c member in engagement with said arm having a hook at its upper end designed to normally engage said locking-bar, and connections between said locking member and the trolley, substantially as set forth.

8. In a trolley-retracting device, the combination with a casing having an open front and ends, and a shaft and locking-bar mounted, respectively, in the lower and upper ends of said casing, of a retractor-arm mounted on said shaft, a spring tending to swing said arm outwardly from said casing, said arm carrying an open frame, a face-plate on the outer side of said arm with a tenon fitted within said frame, a locking-plate secured to and movable with said face-plate on the inner side of said arm, a spring tending to hold said locking-plate at the lower end of said frame, a shoulder on the upper end of said locking-plate designed to normally engage said locking-bar, the outer face of said shoulder being rounded, and a trolley-catcher mounted on said face-plate and connected to the trolley, substantially as set forth.

In testimony whereof I have signed this specification in the presence of two subscribing witnesses.

RICHARD H. HAM.
